UNITED STATES PATENT OFFICE.

JOSEPH BODERMAN, OF NEW YORK, N. Y.

DESIGN FOR A HANGING LAMP.

42,455.

Specification for Design.

Patented May 7, 1912.

Application filed May 6, 1911. Serial No. 625,652. Term of patent 7 years.

To all whom it may concern:

Be it known that I, JOSEPH BODERMAN, a citizen of the United States, residing at New York, in the county of New York and State of New York, have invented a new, original, and ornamental Design for Hanging Lamps, of which the following is a specification, reference being had to the accompanying drawing, forming part thereof.

The figure of the drawings is a side elevation of the lamp showing my new design.

I claim:

The ornamental design for a hanging lamp, as shown.

JOSEPH BODERMAN.

Witnesses:

TOM. BRABSORE,
BEATRICE MIRVIS.
